MACHINE FOR USE IN OPERATING UPON
SHOE UPPERS

Axel A. Lawson, Beverly, Mass., assignor to
United Shoe Machinery Corporation, Borough
of Flemington, N. J., a corporation of New Jersey

Application February 13, 1939, Serial No. 256,055

60 Claims. (Cl. 12—97)

This invention relates to machines for use in operating upon shoe uppers and it is illustrated herein with reference to shaping the heel or back parts of uppers preparatory to assembling them with insoles in constructing the shoes.

It has always been difficult in assembling uppers with insoles, preparatory to the subsequent operations in constructing the shoes, to position and fit the heel or back part of the upper, commonly referred to as the quarter portion, on the rear or heel portion of the last in such a manner that the back part of the upper will hug the heel portion of the last closely and smoothly at all parts thereof and can be maintained in this close fitting relation during the subsequent operations referred to, that is to say, so that the back part of the upper will be held with its back seam or a line corresponding thereto, located in a straight position heightwise of the last and with the top and side portions of said back part, including the "wings" of the counter stiffener and the adjacent materials of the upper, conforming closely to the curves at corresponding portions of the last. This difficulty arises from the peculiar configuration of the heel portion of a last which has a curvature both laterally and heightwise which tends to resist or render ineffective all attempts to obtain a close and accurate fit or conformation of the upper to the heel portion of the last, these attempts usually involving some sort of a shaping or molding operation preliminary to the assembly of the heel portion of the upper on a last.

Other circumstances which militate against obtaining an accurate and close fit of the back part of the upper to the heel portion of the last are that the back part, at least in the ordinary shoe, is made up of several different layers of materials, namely, an outer layer of leather or fabric or substitutes for such materials, a lining of fabric or thin flexible leather, and a counter member or stiffener composed of fiber or a similar relatively inflexible material. Each of these layers has characteristics or qualities peculiar to itself and different from those of the other layers such, for example, as tensile strength, resiliency, elasticity and so forth and, accordingly, when these layers are joined together in a single unit or assembly, they react differently to pressures or stresses applied thereto in the manufacture of the shoe and these different reactions tend to cause wrinkles, looseness between the layers, and other disadvantages which are not easily eradicated from the shoe.

While the attempts that have been made in the past to overcome the difficulties in obtaining a 55

close and accurate fit of the back part of an upper to the heel portion of a last, usually, as stated, by subjecting the back part assembly to pressure applied in various ways by molds shaped in accordance with the heel portion of a last, have been partially successful in that they have eliminated or reduced some of the difficulties encountered, they have not entirely solved the problem and many difficulties still exist which are a constant 5 source of trouble and expense to the manufacturer.

Since the recent increased popularity of the so-called two-part sandal type shoe the above problem has become more acute because the back part of the upper of such a shoe, although formed as a complete unit or assembly as in other shoes, is usually made up and assembled in the shoe separately from the forepart or vamp portion of the upper. This back part assembly, however, is required to fit the heel portion of the last closely and accurately if a good shoe is to be made notwithstanding the fact that there is no integral vamp or forepart on this type of upper assembly and sometimes, as in the so-called "open shank" shoes, no appreciable shank portion to assist in holding the back part unit in close fitting relation to the heel portion of the last. Moreover, the back parts of both types of uppers, that is, the full length or "closed" upper of the ordinary shoe and the back part assembly of the two-part sandal must, in accordance with the practices referred to, be flanged at their lower marginal portions to cause these portions to overlap the heel seat portions of the insoles and lasts 10 before the uppers are assembled with their insoles. Additional difficulties have arisen in connection with this operation due to excessive and uneven wrinkling of the materials which constitute the flange and the impossibility of maintaining the flange in a proper bent position. Since these difficulties have never been fully overcome they have further complicated the problem.

An object of the present invention is to provide an improved machine for use in operating upon 15 shoe uppers with the aid of which the above difficulties may be eliminated or greatly reduced.

To the attainment of this object the invention provides, in accordance with one feature, an improved machine having means arranged to hold or support a shoe upper with a portion of its back part free or unsupported, a member arranged to clamp the upper in such position in the machine, and means carried by the supporting means for engaging and exerting pressure on the free or unsupported portion of the upper while

the upper is thus clamped to stretch said unsupported portion relatively to the rest of the upper. In addition to stretching a predetermined localized portion of the back part of the upper, the machine is arranged to apply to the back part, including the previously stretched portion, a brief molding pressure to impart to the back part a shape which corresponds closely to the heel portion of a last.

As herein illustrated, the supporting means comprises a work support shaped substantially like the heel portion of a last or, if desired, shaped to exaggerate somewhat the curvatures at the heel portion of a last, and provided at its central portion with an opening which is bridged or spanned by the back part of the upper when it is mounted on the support. The clamping member is arranged to engage the upper on the work support and clamp it in a curved position which simulates the shape it will assume on a last or in a shoe. The pressure exerting means, as herein illustrated, comprises a plunger carried by the work support and movable in the opening for engaging the localized intramarginal portion of the back part assembly which bridges the opening and stretching such portion a predetermined amount which is preferably beyond the limit of the elastic recovery or elasticity of the materials forming the back part of the upper, or at least is beyond the elastic recovery of the counter stiffener of the back part assembly, thereby rendering the stretched materials relatively inert or limp to prevent their reacting sufficiently when pressure is relieved to return to their original condition. The brief molding operation on the back part assembly is accomplished by the co-operative action of the work support, clamping member and plunger after the latter has stretched the intramarginal portion of the back part.

Another feature of the invention comprises the provision of means in the illustrated machine for pleating or corrugating the lower marginal portion of the materials forming the back part assembly coincidently with the stretching of the intramarginal portion thereof and also for creasing said marginal portion along the line where the flange is to be formed, the corrugating means, as illustrated, comprising a plurality of radially extending projections or ribs on the work support which are caused to corrugate the lower margin of the back part assembly by the pressure of the clamping member while the back part is bent into substantially the shape it will assume on a last or in a shoe. The creasing of the back part along the line where the flange is to be formed is accomplished by a member arranged to extend beyond the operating surface of the work support so that it will be forced against the upper by the clamping pressure.

Still another feature of the invention resides in the provision of means for tensioning the upper on the work support before it is clamped, thereby smoothing the upper materials and eliminating wrinkles therefrom, and insuring that all portions of the back part of the upper will be in close fitting engagement with the work support. As illustrated herein, the upper may be tensioned both lengthwise and heightwise and the tension is preferably maintained until after the stretching operation has been completed. The tensioning means comprises a toe clamp movable with, and relatively to, the work support and, as illustrated, gripper members also movable with, and in relation to, the work support for engaging the

upper or its lining and pulling it tightly over the support. The tensioning of the upper before it is clamped not only eliminates any wrinkles that may have been formed in the materials when introduced into the machine, but it also pulls the upper closely against the work support around the upper edge or "top line" of the upper.

With the above and other features and aspects in view, the invention will now be described with reference to the accompanying drawings and will thereafter be pointed out in the claims.

In the drawings,

Fig. 1 is a side elevation partly in section of the machine embodying the present invention, the mechanism being shown in its inoperative position;

Fig. 2 is a perspective view of a back part upper unit or assembly of a two-part upper for a sandal type shoe after the unit has been operated upon by the machine;

Fig. 3 is a perspective view similar to Fig. 2 of the back part unit after a flange has been formed thereon;

Fig. 4 is another perspective view of the unit showing the smooth condition of its inner side after it has been shaped and flanged;

Fig. 5 is a side elevation of the machine in an operative position, parts of the machine being broken away or shown in section;

Fig. 6 is a rear elevation of the upper portion of the machine as viewed from the right in Fig. 5, parts of the mechanism being shown in section;

Fig. 7 is a front elevation of the machine with portions shown in section;

Fig. 8 is a perspective view of a full length or "closed" upper after the heel end or back part thereof has been operated upon by the machine;

Fig. 9 is a perspective view of the back part of the closed upper after it has been flanged;

Fig. 10 is a horizontal section taken on the line X—X of Fig. 5;

Fig. 11 is a horizontal section taken on the line XI—XI of Fig. 5; and

Fig. 12 is a horizontal section taken on the line XII—XII of Fig. 5.

The machine comprises an upstanding frame 20 having bolted to its upper end a U-shaped bracket 22 (Figs. 1 and 6) reinforced on its outer side by ribs 24 and having formed on its inner side a downwardly projecting boss 26 provided with forwardly and rearwardly extending ribs 28. The bracket 22 supports a work clamping or holdown member, indicated generally in the drawings by the numeral 29, and comprising a mold mounted for floating movement by means of a toggle arrangement pivotally connected to the bracket. The bracket 22 is provided at its opposite sides with bosses in which are mounted horizontal pins 30. Pivoted upon each of the pins are a pair of downwardly extending links 32 the lower ends of which are pivotally connected by pins 34 to carrier members 36 (Figs. 1 and 7) comprising relatively thin angle plates reinforced at their opposite edges with ribs 38. The carrier members 36 are pivotally connected or hinged to each other by a horizontal pin 40 which extends through interengaging bosses 42 (Fig. 5) formed on the carrier members. The pivot 40 and the links 32 provide a floating toggle arrangement whereby the members 36 will be caused to swing upwardly and inwardly toward each other when pressure is applied to their lower sides.

Each of the carrier members 36 has a forwardly and rearwardly extending rib 44 on its

upper side adjacent to the pin 40, these ribs being located at all times between the ribs 28 on the bracket 22 to limit or control the lateral swinging movement of the members 36 as they move upwardly under pressure. The carrier members 36 are normally maintained in their lower or open position by a compression spring 46 mounted in the boss 26 and engaging the ribs 44, the spring bearing at its upper end against a shoulder on an adjusting screw 48 in the bracket 22 and provided with a nut 50 for locking the screw in adjusted position, the screw providing means for varying the tension of the spring.

Mounted in each carrier member 36 is a filler block 52 (Figs. 7 and 10) formed of wood or some similar non-yielding material and preferably having an inner surface which conforms substantially to the shape of the back or heel portion of a last laterally and longitudinally, these filler blocks being replaceable by others of different contours for shoes of different shapes or sizes. Located in the opening between the filler blocks 52 is an outer or female mold 54 composed of resilient material, such as rubber or a composition thereof, which is preferably of such firmness or rigidity that it can be deformed only by relatively heavy pressure. As shown in Figs. 7 and 10, the mold 54 is preferably of substantially uniform thickness throughout and covers the inner surfaces of the filler blocks 52 and the opening between the blocks to provide a smooth, continuous clamping or molding surface conforming approximately in shape to the heel portion of a last and especially adapted for clamping and molding the back part of a shoe upper. If desired, the filler blocks 52 may be flat on their inner sides and the mold 54 may have a flat outer side to contact therewith while conforming on its inner surface to the shape of a last.

As best shown in Fig. 7, the lower portion of the mold 54 overlaps the filler blocks 52, thereby holding them in position in the carrier members 36. The mold itself is retained in the carrier members by U-shaped bars 56 secured by screws 58 to the carrier members and having their inner sides projecting upwardly into slots formed in the opposite sides of the mold 54. The forward and rear sides of the mold are confined respectively in the carrier members by plates 57 and 59 secured to said members by screws 61. In order to reduce to a minimum the friction between the work piece and the clamping member or holdown 29 and thereby avoid the formation of wrinkles or creases in the upper materials operated upon, the inner surface of the resilient mold 54 is lined with a layer of leather 60 which is clamped against the lower end of the holdown between the bars 56 and plates 62 by means of screws 64 and is held against the inner confining plates 57 by screws 63.

The work piece to be operated upon is introduced into the machine on a work support or form 66, sometimes called a plug, mounted on the upper end of mechanism which may be referred to generally as a jack 68. The work piece may comprise a back part upper unit or assembly A (Fig. 2) of a so-called two-part sandal type shoe, or it may comprise the back part or heel portion of a full-length upper B (Fig. 8), the latter being commonly known in the art as a "closed" upper. Since the machine is provided with special mechanisms for operating upon a

full length or closed upper B, which are unnecessary when operating upon the back part assembly A, the description of the machine will be made with particular reference to a closed upper, with the understanding that, in the operation of the machine, the results are substantially the same on both types of work. The materials forming the back part of the upper are preferably put into a mulled or tempered condition by moisture prior to being presented to the machine.

The jack 68 is mounted on a piston 70 arranged for vertical reciprocating movement in a cylinder 72 secured to the base of the frame 15 by bolts 74. At its lower portion the cylinder 72 is provided with an opening into which is threaded a pipe 76 connected at its other end to a rotary pump (not shown) arranged to force fluid, such as oil under pressure, into the cylinder to move the piston and jack upwardly and thus force the work support 66 against the holdown 29 with a predetermined pressure for a specified length of time, the pressure for the operation to be performed in the present instance being preferably about 400 pounds to the square inch and the period of pressure being approximately three or four seconds. The operation of the hydraulic power plant may be effected by an electric motor (not shown) which may be controlled by the operator by any usual means such as an electric switch. When the power is turned off the piston 70 descends in the cylinder under the weight of the jack 68, thereby expelling the fluid from the cylinder through the pipe 76. The vertical reciprocating movement of the jack is limited in both directions by a pin 78 extending horizontally through the piston 70 and having its opposite ends projecting into vertical slots 80 in the cylinder 72.

On the upper side of the piston 70 is a pair of upstanding ears 82 between which is mounted for angular adjustment about a pin 84 a supporting block 86 the lower end of which is secured in adjusted position by a set screw 88. Pivotedly connected to the upper end of the block 86 by a pin 90 is a link 92 upon which is formed a lateral projection 93 having a hole therein parallel to the link. A lever 94 of substantial length and integral with the link 92 provides a handle whereby the link 92 may be rotated about the pivot 90. When the mechanism is in its inoperative position, as shown in Fig. 1, the link 92 extends forwardly and the handle 94 is substantially vertical.

Pivotedly connected to the other end of the link 92 by a pin 96 is a coupling 98 into which is threaded for adjustment heightwise of the jack the lower end of a piston 100, a nut 102 being provided for securing the piston in adjusted position relatively to the coupling. The coupling 98 and piston 100, together with the link 92 form, in effect, a toggle arrangement whereby the work support 66 may be raised and lowered relatively to the work clamp or holdown 29 independently of the hydraulic pressure applying mechanism. When the toggle is broken the link 92 extends forwardly and downwardly and the coupling and piston extend upwardly at right angles thereto so that the jack is inclined forwardly toward the front of the machine, as shown in Fig. 1.

The coupling 98 is provided with a hole in which is slidably mounted a locking pin 104, the upper end of the pin being bent at right angles to form a handle. When the toggle 92, 98 is straight the pin 104 is arranged to be inserted

into the hole in the lower link 92 and lock that link rigidly to the coupling 98, thereby preventing the toggle from breaking during the application of pressure to the work piece. When the mechanism is in its idle position with the toggle broken and the jack swung forwardly toward the operator, the pin 104 is withdrawn from the hole in the link 92 and is held away from the link by engagement with a notch 106 formed in the upper end of a plate 108 fastened by screws to the coupling 98.

The piston 100 extends into the lower end of a cylindrical housing 110 and is provided at its upper end with a shoulder 112 (Fig. 5) against which is seated a spring 114 the upper end of which engages the housing and thus yieldingly supports the latter on the piston 100 while allowing relative sliding movement between these two members lengthwise of each other. The piston 100 also carries an upstanding rod 116 which is secured therein by a set screw 118.

The housing 110 projects rearwardly at its upper portion, as viewed in Figs. 5 and 12, and has rigidly secured thereto by bolts 120 an upstanding U-shaped casting 122 which increases in width at its upper end and forms a carrier for the work support 66, the member 122 being referred to hereinafter for convenience as a horn. When the machine is in its inoperative position with the jack swung forwardly toward the operator, the forward inclination of the jack and horn 122 is determined by a chain 124 connected to the horn and to the frame 20. When the toggle 92, 98 is straightened and the jack is located in its operative position, the rearward position of the jack is determined by a roll 126 (Figs. 1 and 11) to locate the jack in a vertical position, the roll being mounted on a pin 128 extending transversely between a pair of fixed arms 130 which project forwardly from the rear side of the frame 20, the arms 130 projecting a sufficient distance forwardly beyond the roll 126 to straddle the horn 122 and thereby serve as a guide for the latter in its rearward and upward movement.

The work support 66 comprises a fixed forward member 132 which is substantially U-shaped in cross section (Fig. 7) and conforms closely to the shape of the heel portion of a last, as best shown in Figs. 5, 7 and 10, although it may, if desired, exaggerate the curvatures of the last. The member 132 has an opening 134 of predetermined shape and size in its upper portion and is secured to the horn 122 by a screw 136. The inner or rear part of the work support comprises a second fixed member 138 shaped to conform approximately to the heel end of a last adjacent to the last bottom, this member being arranged for adjustment heightwise of the horn 122 by a stud screw 140 (Fig. 5) provided with an adjusting nut 142, thereby adapting the work support for operating on uppers of different shapes and sizes. The adjustable member 138 has secured to its forward surface by screws a hardened steel plate 144 the edge face of which projects a short distance beyond the adjacent edge of the member 138. The plate 144 is arranged to produce a crease or indentation around the inner side of the upper materials when they are placed under pressure and thereby establish a line upon which the marginal portion of the upper may be bent inwardly to form the flange at the heel portion thereof. As will be seen in Figs. 1 and 6, the member 138 is corrugated at its upper portion by a plurality of radially extending grooves 146

which converge from front to rear and are adapted to produce radially extending corrugations or pleats in the marginal portion of the upper assembly below the crease referred to above, these corrugations assisting in the formation of the flange on the upper by controlling the distribution of the material as it is bent inwardly around the curve at the heel portion of the last bottom.

Referring to the rod 116 which is secured in the piston 100 by the set screw 118, the upper end of this rod has secured thereto an upwardly extending curved arm 148 which is relatively narrow in cross section, as shown in Fig. 11, and is arranged to reciprocate heightwise between the side walls of the horn 122. At its upper end the arm 148 carries a pin 150 which extends upwardly through holes in the horn and the member 132 and is bored and threaded internally (Fig. 5) to receive an adjustable pin 152 which has secured to its upper end by a set screw 156 a plunger 154 (Figs. 5 and 10). The outer surface of the plunger 154 is shaped to register accurately with the edges of the opening 134 when the plunger is in its upper position, as shown in Figs. 5 and 7, but when the plunger is depressed relatively to the members 132, 138 of the work support, the continuity of the outer surface of the support is broken and a substantial aperture or opening is produced therein directly opposite the heel end of the last and approximately at the point of greatest curvature heightwise thereof. When the plunger is elevated the continuity of the work supporting surface of the support is restored and the back part or heel portion of the upper will be engaged at its intramarginal portion and stretched by the plunger into conformity with the clamping mold or holdown 29 and will thereafter be compressed or molded between the holdown and an inner mold or work support 66, including the plunger 154, so that the back part of the upper will, in the ultimate result, have been subjected to a stretching operation at a localized or intramarginal portion thereof and also to a brief molding operation over the entire back part, including the portion which was stretched by the plunger.

It will be seen from Fig. 1 that when the closed upper B is first mounted on the work support 50 with the plunger 154 in its lower position, the intramarginal portion of the back part of the upper which bridges the opening 134 will be free of the support and substantially flat or straight heightwise of the upper. After the heel portion 55 of the upper has been clamped against the work support 66 by the holdown 29, the plunger 154 is elevated to engage the straight portion of the upper. Continued upward movement of the plunger into alignment with the supporting members 66 and 138 exerts on this straight portion of the upper a stretching action which stretches and conforms the back part of the upper accurately to the curvature of the heel end of a last. The construction is such that there is no appreciable stretching of the clamped portions of the back part assembly, thereby confining the stretching action primarily to the localized intramarginal portion of the back part engaged by the plunger. Moreover, the amount of stretching is controlled or limited by the outer mold or clamping member 29 and by a flat surface 158 on the arm 148 which is arranged to engage the lower surface at the upper end of the horn 122, as shown in Fig. 5.

It should be explained at this point that the

term "conforming," as used herein, is intended to refer particularly to the stretching or deforming of the upper materials as distinguished from the molding or compressing of these materials between a pair of coacting molds having continuous molding surfaces. The term "molding," on the other hand, is intended to denote a genuine molding or compressing operation between continuous molding surfaces which act to "set" or stabilize the upper materials by compression. The action of the work support 66, holddown 29, and plunger 54 on the heel portion of the upper, therefore, in accordance with the foregoing definitions, will be a molding action at all clamped portions of the upper and a stretching or conforming operation followed by a brief molding or "setting" operation over the portion engaged by the plunger 154. In order to prevent the formation of creases or wrinkles in the lining of the upper, the work support is covered with a thin sheet of stretchable material 159, such as rubber, fastened over the support by a plurality of hooks 161.

The operation of the jack in causing the work piece to be clamped between the work support and the holddown and also in causing the plunger 154 to operate to stretch and subsequently mold a localized portion thereof is as follows: A work piece comprising, for example, a pre-assembled closed upper such as B, having its counter stiffener preferably in a flat unmolded condition, is placed over the last-shaped work support 66, as shown in Fig. 1, with its heel portion opposite the plunger 154 and bridging the opening 134. After locating and tensioning the upper in a manner to be later described, the operator swings the jack inwardly about the pivot 96 and moves the handle 94 into the position shown in Fig. 5, thereby swinging the link 92 upwardly and rearwardly and straightening the toggle 92, 98 to move the work support 66 upwardly into engagement with the holddown 29. He then starts the power-operated hydraulic mechanism to elevate the piston 70 which moves the piston 100 upwardly against the spring 114. After compression of the spring a predetermined amount, the housing and horn 122 move upwardly to bring the upper yieldingly against the holddown 29. Upward pressure against the holddown forces the pivot 40 upward against the spring 46 and the two pairs of links 32 swing inwardly about their pivots 30 to close the holddown forcibly around the work support and into clamping relation with the work piece. Throughout this movement the toggle 92, 98 is locked in its straight position by the pin 104 which was inserted in the toggle link 92 before the power was started.

After the work piece has been clamped as described, upward movement of the plunger 70 and horn 122 ceases but the piston 100 continues to move upwardly to further compress the spring 114 and to move the arm 148 and plunger 154 positively upward until the upper end of the arm engages the horn 122 and the outer surface of the plunger registers with the edges of the work supporting members 132, 138, thereby stretching the straight intramarginal portion of the upper which bridges the opening 134 into conformity with the plunger and the clamping member or mold 54. The stretching movement of the plunger, while being insufficient to break the upper materials, is sufficient to stretch the several layers of material at the central or intramarginal portion of the back part assembly beyond the lim-

its of their elastic recovery, that is to say, beyond the limits of their complete elastic recovery or their elasticity. Accordingly, after being stretched these materials can not react and return to their original condition. Since the tensile strengths or resistances of the different materials forming the heel portion of the upper, as well as their powers of recovery or resiliences, will usually differ considerably from each other, the operative movement of the plunger is determined by the pressure required to stretch the counter member or stiffener, as it is sometimes called, beyond the limit of its elasticity, the fibrous material of counter stiffeners being substantially of uniform strength and resiliency in all types of shoes.

As stated above, it is desirable to have the upper or back part assembly tensioned over the work support to insure that the heel portion thereof is in close engagement with the members 132 and 138 of the work support and also to insure that the portion bridging the opening 134 is taut about the support. To this end the machine is provided with a toe clamp or gripper arranged to grip the toe portion of a full length or closed upper somewhat forwardly of the tip line. The toe clamp comprises a curved inner plate 160 arranged to engage the lining of the upper at the toe end thereof and a correspondingly curved plate 162 movable relatively to the inner plate for clamping the upper against said inner plate, the outer plate being preferably covered with leather 163 (Fig. 11) or similar material secured to it by screws 164 to prevent scarring the upper. The inner clamping plate 160 is provided at its central portion with two forwardly and upwardly extending integral arms 166 which carry at their outer ends a horizontal pin 168. Pivoted on the pin 168 is a lever 170 which is pivotally connected at its inner end by a pin 172 to a link 174. The inner end of the link 174 is bifurcated to form ears (Fig. 11) which are pivotally connected by screws 176 (Figs. 1 and 11) to ears on a plate 178 the lower end of which is pivotally mounted on a pin 180 (Figs. 1 and 5) carried by the arms 166. Also pivoted on the transverse pin 180 is an upstanding member 182 which supports the outer clamping plate 162, the latter being arranged by a ball and socket joint for universal movement to permit the clamp to adjust itself properly against the inner plate 160. An adjusting screw 184 threaded through the plate 178 bears against the member 182 so that the position of the latter may be varied relatively to the lever 170 and thereby permit variation of the pressure of the two clamping plates. The construction of the lever 170 and link 174 comprises, in effect, a toggle arrangement which, when the toggle is straight as shown in Fig. 5, holds the outer clamp 162 positively against the inner clamp 160 to grip the toe portion of the upper. A pair of springs 186 (Figs. 1 and 11), connected at their forward ends to the pin 168 and at their inner ends to the upstanding member 182, are provided for urging the outer clamp 162 away from the inner clamp when the toggle is broken. In the operation of the toe clamp, the toe portion of the upper is introduced by the operator between the two clamping plates and the lever 170 is swung downwardly to straighten the toggle and thus clamp the work. After the toe portion of the upper has been gripped in the manner described, the toe clamp or gripper is moved downwardly in a vertical direction to tension the upper about the work support 66. To accomplish this there is provided

a substantially U-shaped casting 188 (Figs. 1 and 11) having forwardly extending ears 190 which are fastened to the lower portion of the horn 122 by screws 192. At its rear portion the casting 188 has upwardly projecting side walls 194 provided with horizontal slots 196 forming guideways in each of which is mounted for forward and rearward movement relatively to the jack a substantially T-shaped guide member 198 provided with a horizontal slot 200 (Fig. 1) through which a thumb screw 202 passes for securing the guide member in adjusted position in the slot 196. The forward portions of the guide members 198 extend heightwise of the jack and are provided with slots 204 and reinforcing lugs 205. The opposite end portions of the inner toe clamp 160 are provided with lugs into which are threaded screws 206 which ride in the slots 204 and thus cause the tensioning movement of the toe clamp to be always in a direction heightwise of the jack or, when the jack is in its operative position, in a vertical direction. Moreover, the path of this movement will also be in a plane which is substantially parallel to the plane of the bottom of the heel end of the last upon which the upper is to be mounted in constructing the shoe.

Pivoted connected to the screws 206 are forwardly and downwardly extending links 208 which are pivotally connected at their lower ends by screws 210 to the forward portion of a yoked lever 212 (best shown in Figs. 1 and 12) having rearwardly extending arms which straddle the housing 110 and are pivotally connected at their rearward ends by a pin 214 to a projection 216 formed on the lower portion of the horn 122. At its forward end the yoked lever 212 is provided with a handle 218 whereby the lever may be rotated downwardly about the fixed pivot 214 to pull the toe clamp downwardly through the aid of the links 208.

In order to lock the toe clamp in its lowered position and thus maintain the tension on the upper, the yoked lever 212 carries a latch 220 (Fig. 5) movably secured to the lower side of the lever 212 by a slot and screw connection 221, the latch being arranged to engage ratchet teeth 223 formed on an upstanding bar 222 pivotally connected by a pin 224 to a plate 226 adjustably secured by screws 228 (Figs. 1 and 12) to a shoulder or flange on the lower end of the housing 110. The upper portion of the bar 222 is guided in an opening in the yoked lever 212 and the latch 220 is normally urged into engagement with the ratchet teeth 223 by a spring 230 extending between the latch and a projection on the handle 218. A latch releasing handle 232 is pivoted at 234 on the handle 218 and is connected to the latch by a link 236 to permit the latch to be released manually from locking engagement with the ratchet when it is desired to relieve the tension on the upper.

It is desirable, when operating on uppers of different shapes and sizes, to adjust the toe clamp angularly to meet different conditions and to this end the left-hand side of the inner clamping member 160, as viewed from the front of the machine, has formed integrally therewith a downwardly extending arm 238 the lower portion of which comprises a segment 240 struck from the center 206 and provided with a slot 242 (Fig. 1). A screw 244 (Fig. 11) extends through the slot in the segment 240 and into the adjacent link 208 to secure this link and the arm rigidly together and thereby to determine the initial angular position of the arm and the inner clamp-

ing plate 160. Adjustment of the screw 244 along the slot 242 varies the angular position of the plate 160 about the center 206.

In addition to tensioning the work piece lengthwise over the work support 66, means is provided for exerting heightwise tension on the upper or back part assembly by engaging and tensioning the upper or its lining at the heel portion thereof to insure that the lining lies smoothly over the work support and also to assist in bringing the upper edge or "top line" of the upper into close engagement with the work support. Adjustably secured to the back portion of the horn 122 by slot and screw connections 246 is a bracket 248 the upper end of which extends at right angles to its lower portion and is provided with a T-slot 250 in which is mounted a slide 252. At its forward end the slide is provided with an upwardly extending boss 254 (Fig. 5) to which is secured by a screw 256 a cross piece 258 provided with forwardly extending gripper jaws 260 (Fig. 10). Pivoted to the left-hand end of the cross piece 258, as viewed from the front of the machine, by a pin 262 is a lever 264 carrying a forwardly extending gripper jaw 266 which co-operates with the fixed gripper jaw 260 and has a rearwardly extending portion secured by a pin 268 to a lever 270 of sufficient length to form a handle 272. Pivoted on a pin 274 in the opposite end of the cross piece 258 is another lever 276 provided with a forwardly extending gripper jaw co-operating with the adjacent fixed jaw 260 and extending rearwardly of the pivot 274, as shown in Fig. 10. Pivoted on the rear portion of the lever 276 by a pin 278 is a second lever 280 the rear end of which is pivotally connected by a pin 282 to a link 284 extending toward the lever 270 and pivotally connected thereto by a pin 286. The foregoing construction provides two pairs of gripper jaws for gripping the lower marginal portion of the lining of the upper at its opposite sides and tensioning the lining by pulling it downwardly or, as viewed in the machine, rearwardly of the work support which is equivalent to pulling the lining downwardly on a last.

To open and close the gripper jaws the lever 272 is swung about the pivot 268 to break or straighten the toggle formed by the link 284 and the inner portion of the lever 272. To maintain the toggle mechanism in a proper position there is provided a rearwardly extending arm 288 rigidly secured to the cross piece 258 by the screw 256, the rear portion of the arm having a slot 290 in which the toggle pin 286 travels. To accommodate different thicknesses of materials the movable jaws 266 and 276 may be adjusted relatively to the fixed inner jaws 260 by a pair of adjusting screws 292, 294 (Fig. 10) extending through the lever 280 and bearing against the lever 276. To make the adjustment the operator loosens the vertical screw 256 and releases the arm 288 and he then loosens one of the adjusting screws and tightens the other, or vice versa, sufficiently to change the leverage between the levers 276 and 280, which action swings the arm 288 in a direction to effect a corresponding movement of the lever 264 carrying the movable jaw 266. After the proper adjustment of the jaws is obtained, the operator tightens the screw 256 to lock the arm 288 in adjusted position.

After the lining of the upper has been gripped by the gripping jaws through straightening of the toggle 272, 284, the slide 252 is moved rear-

wardly to pull the lining in that direction and tension it rearwardly of the work support or heightwise of the upper itself. Rearward and forward movement of the slide is accomplished by a hand wheel 296 (Figs. 6 and 10) keyed to a shaft 298 which carries on its inner end a pinion 300 arranged to mesh with gear teeth 302 formed on the bottom of the slide 252. In order to lock the slide in its rearward position after tension has been applied to the lining, a boss 304 on the bracket 248 carries a detent 306 (Figs. 5 and 6) arranged to engage ratchet teeth 308 (Fig. 10) formed on the inner surface of the hand wheel 296. The hand wheel is normally urged toward the boss 304 to maintain the ratchet teeth in engagement with the detent by a compression spring 310 surrounding the shaft 298 between the hand wheel and a washer 312 secured to the shaft by a pin 314. In the operation of the lining tensioning mechanism the operator pulls the hand wheel laterally against the tension of the spring 310 to release the detent from the ratchet teeth and he then rotates the hand wheel until the desired tension is obtained, after which he releases the hand wheel which becomes locked automatically through the action of the spring 310.

Although the operation of the machine in stretching and molding the back part or heel portion of an upper will be apparent from the foregoing description, a brief summary thereof will be given for clearness and to insure a proper understanding of the invention. An upper B of the closed type (Fig. 8) usually comprises a full length outer layer 316 of leather, artificial leather or fabric, a fabric or leather lining 318, and, at its back part or quarter portion, a counter stiffener 320 of some fibrous material, the counter stiffener being sometimes, but not always, slightly curved widthwise by an operation in its manufacture and being located between the outer layer and the lining with a coating of cement such as latex or rubber cement on both sides which will cause the inner and outer layers to adhere to the counter stiffener after the cement has set. It may be pointed out that while these back part upper units or assemblies may be put together in different ways, sometimes, for example, by inserting the counter stiffener between the outer layer of the upper materials and the lining after the outer layer and lining have been stitched together around one edge to form a "pocket," and sometimes by placing the three layers or plies of the upper upon each other while flat with cement therebetween, pressing the layers together, and then stitching around their peripheries through all three layers and trimming the edges thereof, the precise manner of assembling or constructing the back part portion of the upper, whether of the closed type or a back part unit for a two-part sandal type shoe, is immaterial so far as the present invention is concerned.

The back part of the upper is bent to impart thereto a substantially U-shaped curve and the upper is introduced into the machine with its assembled back part engaging the work support 66 and its inner or lower marginal portion overlying the member 146 of the support the amount which is to form the flange around the lower edge of the upper. In the case of the full length or closed upper B, the toe portion is inserted in and gripped by the toe clamp 160, 162, and the upper is placed under lengthwise tension by actuation of the handle 218 to draw the back part tightly around the work support, this tension being maintained by

the locking pawl 220. The tensioning of the closed upper lengthwise in this manner removes any wrinkles that may have been formed in the lining or the outer layer of the back part when the upper was bent into a U shape over the work support.

The opposite sides of the lining 318 of the closed upper are next inserted into the gripper jaws 260, 266 and 276 and the lining is placed under heightwise or rearward tension to straighten it on the work support, and also to cause the top line of the upper to be pulled tightly against the support, by actuation of the lever 272 which operates the toggle 270, 284, the tension being maintained, as described above, by the detent 306 and ratchet teeth 308. The tensioning of the back part assemblies heightwise, or rearwardly with respect to the machine, eliminates wrinkles and smooths out and straightens the lining in the same manner that an operator does manually with pincers over a last in the so-called "spindling" operation prior to the side lasting and heel seat lasting operations on a shoe, except that, in the present case, the upper is not mounted on a last at the time and no assembling or pulling-over operations have been performed thereon. In the case of a back part upper assembly for a sandal type shoe, in which the materials forming the back part may have been stitched together during its construction, the opposite side portions of the assembly may, if desired, be inserted in the gripper jaws and tensioned heightwise or rearwardly of the work support in the manner just described.

The jack is swung inwardly into operative position about the pivot 96 and the handle 94 is lowered to elevate the jack and bring the upper into engagement with the mold 54 of the clamping member or holdown 29. The locking pin 104 is inserted in the toggle link 92 to prevent the toggle from breaking while pressure is being applied and the power is started to cause the hydraulic mechanism to elevate the piston 70 and, through the mechanisms already described, to press the work support 66 forcibly against the holdown 29, thereby clamping the back part or heel portion of the upper firmly against the work support except at the intramarginal portion which bridges the opening 134 in the work support, the materials at that portion being free of the support and being substantially flat or straight heightwise of the upper. As the clamping pressure increases through compression of the spring 114, the plunger 154 moves positively upward into engagement with the straight portion of the upper spanning the opening and stretches that portion into accurate conformity with the outer mold 54 of the holdown and, accordingly, into close conformity with the curvature at the heel end of a last. The entire heel portion of the upper, including the localized central portion of the back part engaged by the plunger, is then subjected to a brief molding operation under substantial pressure, after which the machine power is shut off to permit the jack to descend by gravity to its inoperative position where the operator breaks the toggle 92, 98, swings the jack outwardly, releases the tensioning devices, and removes the prestretched and molded upper from the work support.

As mentioned above, the procedure is somewhat simpler when operating on a back part upper unit or assembly of a two-part sandal type shoe such as the assembly A shown in Figs. 2 to 4, inclusive. A unit of this type generally comprises an outer layer 322 of leather or fabric, a

lining 324 of fabric or thin leather, and a counter stiffener of fiber 326 which has been coated on both sides with cement and inserted between the outer layer and lining by one of the methods referred to to complete the assembly. The back part assembly A is presented to the work support 65 usually in a flat or unmolded condition, is bent around the support, and is held in a curved U-shape position by the operator and, if desired, by the gripper members 260, 266 and 276 while the operator swings the jack inwardly and elevates the work support by the handle 94 to move the upper into engagement with the mold 54 of the holdown 29. After the back part assembly has been moved into engagement with the holdown, the operator starts the machine power to subject the back part, or a predetermined localized portion thereof, to the stretching operation described above and to subject the entire back part to a brief molding operation under substantial pressure.

It will be seen from Figs. 2 and 8, which show the uppers or back part assemblies after they have been operated upon by the present machine, that the heel or back parts of both types of uppers have been stretched sufficiently at localized intramarginal portions thereof and while bent into the U-shaped positions they would assume in a shoe to cause these back parts to conform closely to the curves at the heel portion of a last or, if desired, to cause said back parts to curve a little more than corresponding portions of the last. Moreover, the back parts have also been subjected to a brief molding operation under substantial pressure which causes their side or "wing" portions to simulate the curves at the opposite sides of the heel end of the last. The lower marginal portions of the assembled back parts have also been corrugated or pleated while held in the position referred to under the clamping and molding pressure to produce pleats or ridges 328 and 330 (Figs. 2 and 8 respectively) which converge inwardly, or radially as viewed from above, and greatly facilitate the formation of the flange on the lower margin of the upper by controlling the distribution of the marginal material when the flange is bent, especially around the curve at the heel end of the last bottom.

It should be pointed out that uppers which have had their back part assemblies treated in the manner described above, whether closed uppers or back part units for two-part sandal shoes, may, if desired, be assembled with their insoles on lasts without any further preparation and subjected to the usual operations in constructing the shoe, namely, the pulling-over operation and the side, toe and heel seat lasting operations, the heel seat lasting operation serving in such case to mold the back part of the upper again into close conformity with the shape of the heel portion of the last, through the action of the heel band or molds of the heel seat lasting machine, and operating also to bend the lower marginal portion of the back part assembly inwardly by means of wipers or plates to form the flange on the back part of the upper, after which the usual heel seat fastenings will be inserted to complete the lasting operation. The condition of these back part upper assemblies is such, therefore, at the completion of the stretching and molding operations, that the uppers may, if desired, be assembled with their insoles on lasts and the construction of the shoes may be completed without further conditioning of the back parts, thereby

eliminating, for example, any special flanging operation or further molding of the back part.

It is sometimes desirable to subject the back parts of the uppers to further preparation before assembling them with insoles either on lasts or separately from lasts, particularly with respect to the back parts of two-part sandal type shoes because these back parts are often assembled with their insoles without the usual heel seat lasting operation and must, therefore, be flanged at their lower marginal portions prior to such assembly so they can be built into the shoe. In order to complete the preparation of such back parts and put them into proper condition for assembly with their insoles, the uppers, as indicated above, may be subjected to a flanging operation in any conventional type of counter molding machine, in which case the pre-stretched and molded back parts will again be molded to the shape of a last during the flanging operation. The pre-shaped back part may, for example, while still in temper or a "mulled" condition, be mounted in a counter molding machine of the type disclosed in Letters Patent of the United States No. 467-473, granted January 19, 1892, on an application filed in the name of William C. Stewart, and it may be flanged by the wipers of such machine during which operation it will also be subjected to molding pressure between the coacting molds of the machine for a sufficient period of time to insure that the several layers of the back part assembly will become permanently "set" or stabilized in the desired shape and position. This additional molding of the back part assembly further compresses the materials thereof and causes these materials, including any extra material produced by the initial stretching operation, to assume the desired last-like shape without setting up any internal tensions or strains which would tend subsequently to urge the materials out of their molded shape or position. It will be seen that, since the materials at the intramarginal portion of the back part of the upper have been stretched beyond the limit of their resiliency or elastic recovery, the fibers of these materials will have become relatively inert and limp and will have practically no tendency to react and return to their original unmolded shape or condition. In cases where either the lining or the outer layer of the back part assembly may not have been stretched beyond the limit of its elastic recovery in the stretching and molding operation, the relatively rigid counter stiffener, which is always stretched beyond the limit of its elastic recovery, will prevent a return of these materials to their original condition after the cement between the counter stiffener and these other layers has set or become tacky. Accordingly, the last-like shape imparted to the heel portion of the upper will be retained indefinitely due in a large measure at least to the stretching and molding of the back part in the present machine.

In molding the back part of the upper in a counter molding machine of the type referred to, the lower marginal portion of the back part is turned inwardly substantially at right angles to its main portion to form the flange by a pair of wipers or plates arranged to be swung inwardly about a pivot over the marginal portion of the upper or back part extending beyond the molds. In forming the flange considerable downward pressure may be exerted on the upper margin to insure that the flange will remain substantially at right angles to the body portion of the upper.

The flange formed on the back part assembly A of a sandal type shoe is indicated by the numeral 332 in Fig. 3 and, in the closed upper B, by the numeral 334 in Fig. 9.

It will be found that the accurate and close fitting relation of the heel or back part portions of these uppers to the heel portions of their lasts which can be obtained through the practice of the present invention renders it unnecessary to mount the uppers on lasts, unless such procedure is preferred, when assembling them with their insoles in constructing the shoe, or to perform the usual pulling-over and heel seat lasting operations prior to the attachment of the outsole. Instead of performing these operations, the back part of the upper may be assembled with its insole and secured directly thereto by fastenings such as tacks, staples or similar means without subjecting the back part to a pulling-over operation either before or after the forepart of the upper has been lasted to the insole. The outsole may then be applied and attached to the shoe in any desired manner as, for example, by nails, stitches or cement. If it is preferred to perform the usual pulling-over and lasting operations, particularly at the heel seat portion of the shoe, the accurate and close fit of the back part assembly to the heel portion of the last will greatly facilitate that procedure because there will be very little tendency to displace the back seam of the upper during such operations or, especially in the closed upper, practically no tendency to set up internal stresses or strains in the upper materials which might cause wrinkles or subsequent displacement of the materials or otherwise interfere with the close and accurate fit of the back part of the upper to the heel portion of the last.

The methods of making shoes and shaping shoe uppers, as well as the shoe upper per se, have not been claimed herein since they form the subject-matter of a copending application Serial No. 305,619, filed November 22, 1939 in my name as a continuation in part of the present application.

Having thus described my invention, what I claim as new and desire to secure by Letters Patent of the United States is:

1. A machine for operating upon shoe uppers having, in combination, a work support arranged to hold an upper with a portion thereof free of the support, a member arranged to clamp the upper against said support, and means for engaging the free portion of the upper from behind the work supporting surface and exerting pressure thereon outwardly of the support.

2. A machine for operating upon the back parts of shoe uppers having, in combination, a work support arranged to hold an upper with a portion of its back part unsupported, a member arranged to clamp the upper against said support, and means for engaging the unsupported portion of the upper from behind the work supporting surface and stretching said portion.

3. A machine for operating upon the back parts of shoe uppers having, in combination, a work support arranged to hold an upper with a portion of its back part unsupported, a member arranged to clamp the upper against said support, said member being also arranged to mold the upper to the shape of said support, and means for engaging the unsupported portion of said back part and stretching it relatively to the clamped portion of the upper and for thereafter

applying molding pressure to said unsupported portion.

4. A machine for operating upon the back parts of shoe uppers having, in combination, a work support provided with an opening, a member arranged to clamp an upper against the work support with a portion of the upper bridging said opening, and means mounted on the work support for stretching that portion of the upper which bridges the opening from behind the supporting surface of the work support.

5. A machine for operating upon the back parts of shoe uppers having, in combination, a work support provided with an opening, a member arranged to clamp an upper against said support with an intramarginal portion of the upper bridging the opening, and means operating in said opening for stretching the portion of the upper which bridges the opening from behind the work supporting surface.

10 6. A machine for operating upon the back parts of shoe uppers having, in combination, a work support arranged to hold an upper with its back part approximating the curved shape it will assume in a shoe, a member arranged to clamp the upper in said shape on the work support, and means separate from but mounted on said work support for engaging and stretching a portion of the back part of said upper.

15 7. A machine for operating upon the back parts of shoe uppers having, in combination, a work support arranged to hold an upper with its back part curved into substantially the shape it will assume in a shoe but with an intramarginal portion of said back part bridging an opening in the support, a member arranged to clamp the upper against the support around said intramarginal portion, and means for exerting pressure on said intramarginal portion to stretch it relatively to the clamped portion of the upper outwardly of said support.

20 8. A machine for operating upon the back parts of shoe uppers having, in combination, a work support shaped substantially like the heel portion of a last and having an opening therein, a member arranged to press the back part of an upper against said support with an intramarginal portion thereof bridging said opening, said member being also arranged to co-operate with said support in applying molding pressure to all portions of said back part except the intramarginal portion bridging the opening, and means operating in said opening for engaging and stretching said intramarginal portion and for thereafter co-operating with the pressing member in applying molding pressure to said intramarginal portion.

25 9. A machine for operating upon the back parts of shoe uppers having, in combination, a work support arranged to hold an upper with its back part curved substantially as it will be in a shoe except for an intermediate portion of said back part which is held relatively straight heightwise thereof, a member arranged to clamp the upper against the support completely around said intermediate portion, and means located in the support for engaging said intermediate portion and forcing it from its straight condition into conformity with the curvature of the rest of said back part, thereby stretching said intermediate portion.

30 10. A machine for operating upon the back parts of shoe uppers having, in combination, a work support having an opening therein, a member arranged to clamp an upper against said work support with a portion of its back part

spanning said opening, mechanism for moving the work support toward the clamping member to clamp the upper, and means actuated by said mechanism for stretching the portion of the back part of said upper which spans the opening in the work support.

11. A machine for operating upon the back parts of shoe uppers having, in combination, a work support shaped substantially like the heel portion of a last, a member arranged to clamp an upper against said work support with the back part of the upper curved as it would be on a last, mechanism for effecting relative movement between the work support and the clamping member to cause the latter to clamp the upper against said work support, means carried by the work support for stretching a portion of the back part of said upper, and means for actuating the stretching means after said relative movement has stopped.

12. A machine for operating upon the back parts of shoe uppers having, in combination, a work support shaped approximately like the heel portion of a last, a member arranged to clamp the back part of an upper against said work support, mechanism for effecting relative movement of the work support and clamping member to move said member into clamping relation with the upper, and means actuated by said mechanism after the clamping movement has stopped for engaging and stretching a portion of the back part of said upper.

13. A machine for operating upon the back parts of shoe uppers having, in combination, a work support shaped approximately like the heel portion of a last and having an opening therein, a holddown member arranged to clamp the back part of an upper against said work support with an intramarginal portion of said back part bridging said opening, mechanism for effecting relative movement between the work support and the holddown member to cause the latter to clamp the upper against the work support, and means operating in said opening and actuated by said mechanism for stretching the portion of the back part of the upper which bridges said opening toward said holddown member.

14. A machine for operating upon the back parts of shoe uppers having, in combination, a work support provided with an opening, a member arranged to clamp an upper against the work support with a portion of its back part bridging said opening, and a plunger carried by said work support and movable from a position below said opening outwardly of the work support for engaging and stretching the portion of said back part which bridges the opening.

15. A machine for operating upon the back parts of shoe uppers having, in combination, a work support provided with an opening, a hold-down member arranged to clamp the back part of an upper against said support with a portion of said back part bridging the opening, mechanism for moving the work support toward the holddown member, a plunger carried by the work support below the work engaging surface thereof for engaging the portion of said back part which bridges said opening and stretching said portion, and means for moving said plunger outwardly of the work support.

16. A machine for operating upon the back parts of shoe uppers having, in combination, a work support provided with an opening, a hold-down member arranged to clamp the back part of an upper against said support with an intra-

marginal portion thereof spanning the opening, means for engaging said intramarginal portion and applying pressure thereto, and mechanism for moving the work support against the hold-down member to clamp the upper and for actuating said pressure applying means.

17. A machine for operating upon the back parts of shoe uppers having, in combination, a work support arranged to hold an upper with its back part curved as it would be on a last and with an intramarginal portion of said back part free of the support, a holddown member arranged to clamp the upper against said support, a plunger for engaging the free intramarginal portion of said back part and stretching it, and mechanism arranged to move the work support and holddown member into clamping relation with each other and to actuate said plunger after movement of the work support and holddown member has ceased.

18. A machine for operating upon the back parts of shoe uppers having, in combination, a work support having a surface thereon for receiving an upper, a member arranged to clamp the upper against said support, a plunger mounted on the work support for engaging a portion of the upper on the support and stretching said portion outwardly of said support, and mechanism constructed and arranged to move the plunger a predetermined distance toward the surface of the support to stretch said portion of the upper.

19. A machine for operating upon the back parts of shoe uppers having, in combination, a work support, a member arranged to clamp an upper against said support, a plunger carried by the work support and adapted to engage and stretch a portion of the upper on said support, and mechanism constructed and arranged to move the work support yieldingly against the clamping member to clamp the upper on the support and thereafter to move the plunger positively against the upper to stretch the portion thereof engaged by the plunger.

20. A machine for operating upon the back parts of shoe uppers having, in combination, a work support provided with an opening, a hold-down member arranged to clamp the heel portion of an upper against the support with an intramarginal portion thereof bridging the opening, a plunger mounted on the work support and arranged for movement in said opening for stretching the intramarginal portion of the upper which bridges the opening outwardly of the support, and power operated mechanism for moving the plunger to stretch said intramarginal portion.

21. A machine for operating upon the back parts of shoe uppers having, in combination, a work support provided with an opening, a hold-down member arranged to clamp the heel portion of an upper against the support with an intramarginal portion of the back part thereof bridging the opening, a plunger arranged for movement in said opening for stretching the intramarginal portion of the upper which bridges the opening, and hydraulically operated mechanism for effecting relative movement of the work support and holddown member to clamp the upper on said support and arranged also to move the plunger relatively to the work support to cause it to engage and stretch said intramarginal portion of the upper.

22. A machine for operating upon the back parts of shoe uppers having, in combination, a work support provided with an opening, a hold-

down member arranged to clamp the back part of an upper against said work support with an intramarginal portion of said back part bridging the opening, a plunger carried by said work support and movable in said opening for engaging and stretching the portion of said back part which bridges the opening, mechanism for moving the work support yieldingly against the hold-down member to cause the latter to clamp the upper, said mechanism being also arranged to move the plunger positively against the upper after it has been clamped, thereby stretching the intramarginal portion of the back part of the upper, and means for limiting positive movement of said plunger to control its stretching action.

23. A machine for operating upon the back parts of shoe uppers having, in combination, a work support provided with an opening, a hold-down member arranged to clamp the back part of an upper against said work support with an intramarginal portion of said back part bridging the opening, a plunger carried by said work support and movable in said opening for engaging and stretching the portion of said back part which bridges the opening, means movable toward and from the hold down member for carrying the work support, an arm carried by said carrying means and movable relatively thereto for supporting the plunger, and mechanism for moving the carrying means yieldingly toward the hold-down member to clamp the upper on the work support and for moving said arm positively toward the hold-down member after the upper is clamped to cause the plunger to engage and stretch the portion of the upper which bridges the opening in the work support.

24. A machine for operating on the back parts of shoe uppers having, in combination, a work support having an opening therein, a hold-down member arranged to clamp the heel end portion of an upper on the work support with an intramarginal portion thereof spanning the opening, a plunger movable in said opening for engaging and stretching the portion of the upper spanning the opening, power operated mechanism carrying said work support and arranged to move it toward the hold-down member to clamp the upper on said support, an arm secured to said mechanism and movable therewith for supporting said plunger, and means for permitting the work support to yield relatively to said power operated mechanism after said support has been moved into clamping relation with the hold-down member, thereby permitting said arm and plunger to be moved by said mechanism relatively to said work support into engagement with the portion of the upper spanning the opening to stretch said portion.

25. A machine for operating on the back parts of shoe uppers having, in combination, a work support provided with an opening, a hold-down arranged to clamp the back part of an upper against said support with an intramarginal portion of said back part bridging the opening, a plunger arranged to move in said opening for engaging and stretching the portion of the upper spanning the opening, hydraulic mechanism for moving the work support toward the hold-down to cause the latter to clamp the upper on the support, said plunger being secured to said mechanism and arranged for movement therewith, a spring for permitting the work support to yield relatively to the hydraulic mechanism after the latter has moved the support into

clamping relation with the hold-down, thereby causing the hydraulic mechanism to move the plunger relatively to the work support to engage and stretch the portion of the upper spanning the opening in said support, and means for limiting the movement of the plunger relatively to said work support.

26. A machine for operating upon the back parts of shoe uppers having, in combination, a work support shaped substantially like the heel portion of a last but having the curved continuity of its surface broken by an opening, a member arranged to clamp the back part of an upper against said support with a intramarginal portion of said back part bridging said opening in a substantially flat condition, and a plunger movable in said opening for stretching the flat portion of the upper which bridges the opening, said plunger being so constructed and arranged that, when it has stretched the upper, it will have completed the curved continuity of the surface of the work support.

27. A machine for operating upon the back parts of shoe uppers having, in combination, a work support corresponding substantially in shape to the heel portion of a last but with the continuity of its curved surface interrupted by an opening located in a position corresponding to the back of the heel portion of the last, a member arranged to clamp the back part of an upper against said support with an intramarginal portion of said back part bridging said opening, a plunger movable in said opening to engage and stretch the portion of the upper bridging the opening, said plunger being so shaped that when it is in operative position it will restore the continuity of the curved surface of the work support interrupted by said opening, and means for controlling the stretching movement of said plunger.

28. A machine for operating upon the back parts of shoe uppers having, in combination, a work support corresponding substantially in shape to the heel portion of a last but with the continuity of the back end of its curved surface broken by an opening, a hold-down member arranged to clamp the upper against said support with an intramarginal portion of the back part of the upper bridging said opening, a plunger operating in said opening for engaging and stretching the portion of the upper bridging the opening, said plunger being arranged when operated to complete the continuity of the surface of the work support broken by said opening, means for adjusting the position of said plunger relatively to said opening, and means for limiting the operative movement of said plunger in the opening.

29. A machine for operating upon the back parts of shoe uppers having, in combination, a work support shaped substantially like the heel end of a last and provided with an opening, a hold-down member for clamping the back part of an upper against said support with an intramarginal portion thereof bridging said opening, said member when in an operative position being complementary in shape to the work support except for said opening at which portion said member completes the last-like shape of the support, means for moving the support toward the hold-down member, and means for engaging the intramarginal portion of said back part bridging the opening and forcing it into conformity with the hold-down member, thereby stretching said portion,

said means being arranged to operate after movement of the support has ceased.

30. A machine for operating upon the back parts of shoe uppers having, in combination, a work support shaped substantially like the heel portion of a last, means carried by the support for stretching the back part of an upper mounted thereon, a member for clamping the upper against the work support while it is being stretched, and means for moving the work support against said clamping member, said member being arranged to close yieldingly about the last-shaped work support under pressure from said support.

31. A machine for operating upon the back parts of shoe uppers having, in combination, a work support shaped substantially like the heel portion of a last, means carried by the support for stretching the back part of an upper mounted thereon, and a holdown member for clamping the back part of an upper against the support before it is stretched, said member being pivoted for floating movement relatively to the work support and being arranged to close automatically about said support under pressure therefrom.

32. A machine for operating upon the back parts of shoe uppers having, in combination, a work support shaped substantially like the heel portion of a last, means carried by the support for stretching the back part of an upper mounted thereon, and a holdown for clamping said back part on the support during the stretching operation, said holdown comprising a mold shaped to embrace the work support, members carrying the mold and arranged for opening and closing movement about a pivot, means for supporting said members for floating movement relatively to the work support, and means for normally maintaining said members in an open position.

33. A machine for operating upon the back parts of shoe uppers having, in combination, a work support shaped substantially like the heel portion of a last, means carried by the support for stretching the back part of an upper mounted thereon, and a holdown for clamping the upper against the work support while it is being stretched, said holdown comprising a resilient mold having a continuous surface for engaging the upper, carrier members for said mold pivoted for opening and closing movement about a common axis, links for supporting said members for floating movement relatively to the work support, the construction being such that the mold will be forced to close around the work support in response to pressure therefrom, means for automatically returning the carrier members and mold to open position when pressure thereon is relieved, and means for limiting the floating movement of said members and mold laterally of the work support during their clamping action, thereby causing the clamping pressure to be applied substantially uniformly at opposite sides of the work support.

34. A machine for operating upon the back parts of shoe uppers having, in combination, a work support arranged for swinging movement toward and from an operator, a member for clamping an upper on said support, a plunger carried within said work support for stretching a portion of the upper mounted thereon outwardly of the support, means for moving the work support against the clamping member to clamp the upper, and power operated means for moving said plunger toward the upper.

35. A machine for operating upon the back

parts of shoe uppers having, in combination, a work support pivoted for forward and rearward swinging movement, a holdown member arranged to clamp an upper on said work support, 5 a plunger operable to stretch an intramarginal portion of the upper on the work support, toggle means for moving the work support into engagement with the holdown member, and power operated means for moving said support forcibly 10 against the holdown member to clamp the upper before the plunger is operated to stretch the upper.

36. A machine for operating upon the back parts of shoe uppers having, in combination, a work support arranged for swinging movement toward and from an operator, a holdown arranged to clamp an upper on the work support, said holdown being located in a predetermined idle position relatively to the work support, 15 a plunger for stretching the upper, means for positioning the work support in alignment with the holdown when the support is swung away from the operator, toggle means for moving said support into engagement with the holdown and 20 maintaining it in such position, and mechanism for forcing the work support yieldingly against the holdown to clamp the upper on the support and for positively actuating said plunger to stretch said upper.

37. A machine for operating upon the back parts of shoe uppers having, in combination, a work support arranged for swinging movement toward and from an operator, a holdown arranged to clamp an upper on the work support, 35 said holdown being located in a predetermined position relatively to the work support, a plunger for stretching the upper, means for positioning the work support in alignment with the holdown when the support is swung away from the operator, manually operated means for moving the work support into engagement with the holdown and maintaining it in such position, and mechanism for moving the work support yieldingly against the holdown to clamp the upper 40 and for thereafter moving the plunger a predetermined distance relatively to the work support to stretch the upper.

38. A machine for operating upon the back parts of shoe uppers having, in combination, 50 means arranged to hold an upper with a portion of its back part unsupported, a member arranged to clamp the upper in such position, a plunger for engaging the unsupported portion of the upper and stretching it relatively to the rest of the upper, and means for tensioning the upper on said holding means before it is clamped.

39. A machine for operating upon the back parts of shoe uppers having, in combination, means arranged to hold an upper with a portion of its back part bridging an opening, a member arranged to clamp the upper in such position, a plunger movable in said opening for engaging and stretching the portion of the upper bridging the opening, and means for putting the upper under tension before it is clamped.

40. A machine for operating upon the back parts of shoe uppers having, in combination, means arranged to support an upper in the curved shape it will have in a shoe and with a portion of its back part unsupported, a member arranged to clamp the upper in such position, a plunger for engaging and stretching the unsupported portion of said back part, and means for tightening the upper around the supporting means before it is clamped.

41. A machine for operating upon the back parts of shoe uppers having, in combination, a work support arranged to hold an upper with a portion of its back part free of the support, a member arranged to clamp the upper against said support, a plunger for engaging the free portion of the upper and stretching it relatively to the remaining portion of said back part, and means for tensioning the upper about the work support prior to the operation of said plunger.

42. A machine for operating upon the back parts of shoe uppers having, in combination, a work support provided with an opening, a plunger carried by said work support and operating in said opening for stretching a portion of the upper bridging the opening, means for tensioning the upper around the work support before it is stretched by said plunger, and means for thereafter moving the plunger to stretch the upper while maintained under tension around the work support.

43. A machine for operating upon the back parts of shoe uppers having, in combination, a work support for holding an upper, a holdown member arranged to clamp the upper on said support, means for stretching a predetermined portion of the upper so clamped, and means for tensioning the upper in two directions about the work support before it is clamped, thereby smoothing the upper on the support and preventing the formation of wrinkles therein when it is clamped.

44. A machine for operating upon the back parts of shoe uppers having, in combination, a work support arranged to hold an upper, including a lining, with its back part in the curved shape it will assume in a shoe and with an intramarginal portion of said back part bridging an opening, a holdown member arranged to clamp said back part on the support, a plunger for stretching the portion of the upper bridging the opening, means for gripping the forepart of the upper and tensioning it longitudinally about the support, and means for gripping the opposite margins of said lining and tensioning it about the support heightwise of the upper.

45. A machine for operating upon the back parts of shoe uppers having, in combination, a work support, a member arranged to clamp an upper on the support with its back part curved as it will be in a shoe, a plunger for stretching a portion of said back part, and manually operated means for tensioning the upper about said support both lengthwise and heightwise of the upper before it is clamped.

46. A machine for operating upon the back parts of shoe uppers having, in combination, a work support arranged to hold the back part of an upper, a holdown arranged to clamp said back part on said support, a plunger carried by the work support for stretching a portion of said back part, and means for tightening the upper lengthwise and heightwise about the support before said back part is clamped, said means being constructed and arranged to maintain the tension until released by an operator.

47. A machine for operating upon the back parts of shoe uppers having, in combination, a work support arranged to hold the back part of an upper in substantially the same curved shape it would have on a last but with an intramarginal portion of said back part unsupported, a holdown arranged to clamp said back part on said support, a plunger for stretching the unsupported portion of said back part, and means for

tensioning the upper lengthwise about the support to eliminate wrinkles before the upper is clamped, said means comprising curved members for engaging the inner and outer sides of the toe portion of the upper and gripping said portion, mechanism for actuating said members, and means for moving the curved gripping members relatively to the upper in a plane substantially parallel to the bottom of the heel end of said last to tension the upper lengthwise.

48. A machine for operating upon the back parts of shoe uppers having, in combination, a work support arranged to hold an upper with its back part curved substantially as it would be on the last upon which the upper is to be mounted but with an intramarginal portion of said back part bridging an opening in the support, a member arranged to clamp said back part against said support, a plunger for stretching the portion of said back part bridging the opening, means for tensioning the upper lengthwise about the support, said means being movable relatively to the upper in a plane substantially parallel to the bottom of the heel end of a last with the upper mounted thereon, and means for tensioning the back part of the upper about said support heightwise of the upper, said means being movable substantially at right angles to the above-named plane.

49. A machine for operating upon the back parts of shoe uppers having, in combination, a work support arranged to hold an upper with its back part curved substantially as it would be on the last upon which the upper is to be mounted but with an intramarginal portion of said back part bridging an opening in the support, a member arranged to clamp said back part against said support, a plunger for stretching the portion of said back part bridging the opening, means for tensioning the upper lengthwise about the support, said means being movable in a straight path heightwise of the support, and means for tensioning the upper about the support heightwise of the upper, said means being movable forwardly and rearwardly of the support and at right angles to the path of movement of the first-named tensioning means.

50. A machine for operating upon the back parts of shoe uppers having, in combination, a work support arranged to swing into and out of operative position about a horizontal axis, a member arranged to clamp the back part of an upper yieldingly upon said support, a plunger for stretching a portion of said back part after the upper has been clamped, means movable with the work support for tensioning the upper lengthwise and heightwise about said support before the upper is clamped, said means being movable relatively to the support when tensioning the upper, and mechanism for causing said tensioning means to maintain the tension upon the upper until the latter is to be removed from the work support.

51. A machine for operating upon the back parts of shoe uppers having, in combination, a work support arranged to swing into and out of operative position about a horizontal axis, a member arranged to clamp the back part of an upper yieldingly upon said support, a plunger for stretching a portion of said back part after the upper has been clamped, means movable with the work support for tensioning the upper lengthwise about the support before the upper is clamped, separate means movable with the support for tensioning the upper heightwise about

the support before said upper is clamped, and means for adjusting both of said tensioning means for uppers of different shapes.

52. A machine for operating upon the back parts of shoe uppers having, in combination, a work support shaped substantially like the heel end of a last for supporting the back part of an upper to be stretched by the machine, and means for tensioning said back part about said work support before it is stretched, said means comprising a toe gripper, mechanism for actuating said gripper to tension the upper lengthwise, heel grippers for engaging the opposite sides of the back part of the upper and tensioning it heightwise, and mechanism for actuating said heel grippers.

53. A machine for operating upon the back parts of shoe uppers having, in combination, a work support shaped substantially like the heel portion of a last for supporting the back part of an upper to be stretched by the machine, and means for tensioning said back part about said support before it is stretched, said means comprising a toe gripper shaped to engage the toe portion of the upper, toggle means for actuating said gripper, mechanism for moving the gripper in a straight path lengthwise of the upper to tension the same, means for automatically maintaining said gripper in operative position until manually released, a pair of grippers for engaging the opposite marginal portions of the upper adjacent to the back part, mechanism for moving said grippers at right angles to the movement of the toe gripper, thereby tensioning said back part heightwise about the work support, and means for automatically maintaining said pair of grippers in operative position until manually released.

54. A machine for operating upon shoe uppers having, in combination, a work support arranged to hold an upper with an end portion thereof in substantially the shape it will assume on a last, a member for clamping said end portion including a marginal portion thereof against said support, and means for corrugating said marginal portion while it is clamped against said support.

55. A machine for operating upon the back parts of shoe uppers having, in combination, a work support arranged to hold an upper with its back part in substantially the shape it will assume on a last, a member for clamping said back part against said support, and means for creasing the back part of the upper while so held along the line where a flange is to be formed and for corrugating said back part below the crease.

56. A machine for operating upon the back parts of shoe uppers having, in combination, a work support arranged to hold the back part of an upper comprising an outer layer, lining and counter, in substantially the curved shape it will assume on the heel portion of a last, a member

for clamping said back part against the work support, and a corrugated member on the support for producing radially extending corrugations in the lower marginal portions of the materials of said back part while the back part is held in said curved shape.

57. A machine for operating upon the back parts of shoe uppers having, in combination, a work support arranged to hold an upper with its back part in substantially the shape it will assume on the heel portion of a last, a member for clamping the back part in said shape against said support, and means constructed and arranged to produce a crease on the lower marginal portion of said back part along the line on which the lasting flange is to be bent and for also forming corrugations on the upper below said crease, said means being caused to operate upon the upper by the pressure of said clamping member.

58. A machine for operating upon the back parts of shoe uppers having, in combination, a work support arranged to hold an upper with all but the lower marginal portion of its back part in substantially the position it will assume in a shoe, a member for engaging the back part of the upper and clamping it in such position against the work support, a plate on said work support arranged to produce a crease in the back part of the upper along the line where a heel flange is subsequently to be turned, and radially extending ribs on said support arranged to pleat the upper below said crease, said plate and ribs being caused to crease and pleat the upper by the pressure of the clamping member while the upper is held on the support in the position it will assume in a shoe.

59. A machine for operating upon the back parts of shoe uppers having, in combination, a work support arranged to hold an upper with all but the lower marginal portion of its back part in substantially the position it will assume in a shoe, said support including a ribbed member underlying said lower marginal portion, and a member for engaging said back part and clamping it against the work support, said member being arranged to press the lower marginal portion of the back part against said ribbed member to form corrugations in the lower marginal portion.

60. A machine for operating upon the back parts of shoe uppers having, in combination, a work support for holding an upper with its back part in substantially the curved position it will assume on a last, and means carried by the support for producing a crease in the lower marginal portion of said back part along the line where the back part is subsequently to be flanged and for also forming radially extending pleats below said crease, said means being caused to act upon the upper by direct pressure alone while said back part is held in said curved position.

AXEL A. LAWSON.

CERTIFICATE OF CORRECTION.

Patent No. 2,266,774.

December 23, 1941.

AXEL A. LAWSON.

It is hereby certified that error appears in the printed specification of the above numbered patent requiring correction as follows: Page 5, first column, line 73, for "in" before "sufficient" read --is--; page 9, first column, line 56, claim 1, strike out "outwardly of the support"; and second column, line 48, claim 8, for "potrion" read --portion--; page 10, first column, line 13, claim 11, for "pedal" read --heel--; page 11, first column, line 64-65, claim 25, for "ortion" read --portion--; and that the said Letters Patent should be read with this correction therein that the same may conform to the record of the case in the Patent Office.

Signed and sealed this 17th day of February, A. D. 1942.

Henry Van Arsdale,
Acting Commissioner of Patents.
